DESIGN FOR A TIE HOLDER

Gustav A. Loercher, Greenwood, R. I., assignor to Carl-Art, Inc., Providence, R. I., a corporation of Rhode Island

Application December 2, 1940, Serial No. 97,003

Term of patent 7 years

To all whom it may concern:

Be it known that I, Gustav A. Loercher, a citizen of the United States, residing at Greenwood, in the county of Kent and State of Rhode Island, have invented a new, original, and ornamental Design for a Tie Holder, of which the following is a specification, reference being had to the accompanying drawing, constituting a part hereof:

Fig. 1 is a front view of the tie holder showing my new design; and
Fig. 2 is a plan view thereof.

I claim:
The ornamental design for a tie holder, substantially as shown.
